UNITED STATES PATENT OFFICE.

CHARLES FRANCIS TEBBETTS, OF FITCHBURG, MASSACHUSETTS.

MACHINE FOR ROLLING METAL TO SPHERICAL FORM.

SPECIFICATION forming part of Letters Patent No. 367,682, dated August 2, 1887.

Application filed February 24, 1887. Serial No. 228,794. (No model.)

To all whom it may concern:

Be it known that I, CHARLES FRANCIS TEBBETTS, of Fitchburg, in the county of Worcester and Commonwealth of Massachusetts, have 5 invented certain Improvements in Machines for Making Metal Articles, of which the following, taken in connection with the accompanying drawings, is a specification.

This invention relates to machines for making metal articles spherical, cylindrical, or other contour having circular cross-sectional area; and the objects and nature of this invention are fully described and specifically claimed hereinafter.

15 Referring to the drawings, Figure 1 is a perspective view of the forward end of a machine embodying this invention, a part of one of the supporting-brackets being broken away to better show the working of the platens. Fig. 2 is 20 a view of the platens or die-carrying plates, the positions which the dies are to occupy being indicated thereon by curved lines, while the direction of motion in which the platens are moved while making one of the metal articles is indicated by the arrows. Fig. 3 is a 25 plan view of one of the dies.

This invention pertains to that class of machines in which there are two dies, the same to be used in pairs and moved in opposite directions to shape articles of metal rolled on 30 their axis between.

It is the object of this invention, in part, to prevent the article from slipping and sliding out of position while being formed. To this end I give the dies a lateral curvature (see 35 Fig. 3) and mount them upon movable platens or carrying-plates with the forming-surfaces of the dies opposed to each other. The platens are themselves mounted upon supporting-brackets, and one of said platens, preferably the 40 top one, is made adjustable toward and from the other, to the end that dies of different thicknesses may be introduced between the platens. This adjustment of the platens I accomplish in 45 the machine represented by making the bracket which supports the platen movable on its supporting and staying pins; but it will be evident that other constructions and forms of mechanism may be employed as well. The 50 platens are located one above the other, and are pivotally connected to their supporting-

brackets by suitable pins or studs, on which they may be turned or oscillated sufficiently to carry the forming-dies past each other in opposite directions. In the machine represented I make use of a rack-and-pinion mechanism—the construction, arrangement, and operation of which is deemed obvious from the drawings—for giving movement to the platens; but other mechanisms may be employed as well, 60 the essential feature being to move the dies in opposite directions simultaneously and with equal speed.

The curvilinear face of the die commences at the vanishing point and gradually deepens 65 until it terminates at the opposite end of the die on line. This is the forming-surface of the die. It commences its work at the point and ends it at the line. The maximum depth of the surface on line is about equal to one- 70 half the largest diameter of the article which it is intended to make between the two dies, and the general conformation or contour of this surface on line will correspond with the lateral contour of the completed article as it 75 appears on a plane which bisects the article. The spreading and reducing surfaces, commencing at the point, rise gradually from the surface of the die-block until they terminate on line, at which point they are elevated to 80 one-half the diameter of the intended article. The dies, which are preferably composed of steel, are made by first planing or milling in the groove which constitutes the forming-surfaces and then cross-planing the raised surfaces to a vanishing point, as stated. The outer or spreading surfaces are preferably rounded and corrugated or chased, to the end that they may better lay hold of the metal bar 85 and rotate it while the article is being formed. 90

The curvature of either die is made similar to the curvature of its co-operating member, and the dies are positioned upon their respective platens, so that their forming-surfaces overlap each other and their corresponding 95 surfaces register with each other in a plane that bisects the platen pivotal pins. On either side of this plane the forming-surfaces diverge according to the lateral curvature of the dies, and are therefore non-registrant. In the machine represented the registering line is intermediate the pivotal bearings of the platens, 100

and as the dies move past each other in opposite directions the forming-surfaces converge as they approach and diverge as they depart from the registering plane.

5 In operation the platens are first moved so as to bring the vanishing point of each die into the registering plane. The metal bar is then placed in position between the dies and the platens begin to move in opposite directions, as indicated. The dies lay hold upon opposite sides of the metal bar, and in moving past each other compress, reduce, and shape the intended article, which article drops from the metal bar a completed thing, when the dies complete their passage. It is always in the registering plane that shape and form are imparted to the intended article, and the lateral divergency of the forming-surfaces of the dies immediately before and after the registering plane prevents the article from slipping and sliding out of position while being formed. The dies represented in the drawings are sections or arcs of similar circles, and are mounted upon platens which turn about fixed axes, and 15 I am persuaded to believe that such is the simplest and most economical mechanism and arrangement to be employed in carrying out my invention, though I am aware that other mechanisms could be devised for operating

the dies and carrying them through the required paths or movements and effect the results described; but 30

I claim as of my invention and desire by Letters Patent to secure—

1. In a machine for making metal articles, 35 substantially as described, the combination of curved dies mounted on platens and working in curved paths, substantially as set forth.

2. Curved dies, substantially as described.

3. Two dies having forming-surfaces, substantially as set forth, the dies being arranged with their forming-surfaces opposed and registering with each other in a cross-sectional plane and divergent and non-registering on both sides of said plane, combined with mechanism for moving the dies in opposite directions and bringing the successive cross-sectional surfaces of the dies into the registering plane simultaneously, substantially as and for the purposes described. 40

4. The combination of the curved dies, their supporting-platens, and the described rack-and-pinion mechanism for moving the dies, substantially as described. 45

CHARLES FRANCIS TEBBETTS.
